UNITED STATES PATENT OFFICE.

JOHN F. O'CONNOR, OF CHICAGO, ILLINOIS, ASSIGNOR TO WILLIAM H. MINER, OF CHICAGO, ILLINOIS.

REFRIGERATOR-CAR-DOOR-OPERATING MECHANISM.

1,193,414.

Specification of Letters Patent.

Patented Aug. 1, 1916.

Application filed July 21, 1910. Serial No. 573,069.

To all whom it may concern:

Be it known that I, JOHN F. O'CONNOR, a citizen of the United States, residing in Chicago, in the county of Cook and State of Illinois, have invented a new and useful Improvement in Refrigerator-Car-Door-Operating Mechanism, of which the following is a specification.

My invention relates to improvements in refrigerator car doors and means for opening and closing same.

In the accompanying drawing forming a part of this specification, Figure 1 is a front elevation of a pair of refrigerator car doors provided with my improved operating mechanism. Fig. 2 is a detail plan view of the operating lever showing the operating shaft in horizontal section. Fig. 3 is a detail, partial front view of the operating shaft. Fig. 4 is a side or edge view of same. Fig. 5 is a detail front elevation of one of the bearings for the operating shaft and Fig. 6 is a detail plan view of said bearing.

In the drawing, 1 represents a portion of a refrigerator car, 2, 2 refrigerator car doors, 3 the hinges thereof, 4 the connecting bar of the two-part operating shaft 5, 5, 6, 6 the crank arms at the upper and lower ends of the operating shaft, 7, 7 the keepers secured to the car frame or to the upper and lower sills of the door frame, each having an inner jaw 8 against which the crank arms engage for opening the doors and an outer jaw 9 for engagement with the crank arms in forcing the doors closed, 10 the hasp lever pivotally secured to the connecting bar of the operating shaft by a pin 11 which passes through its jaws 12, 13 the staple member of the door fastener and 14 the swinging latch or lock on the staple member 13.

In order to cause the inner and outer jaws or cam acting faces 8, 9 of the upper and lower keepers 7 to properly coöperate with the crank arms 6 of the operating shaft 5, and thus properly force the doors tightly closed and start them in their opening movement, it is very essential that the crank arms 6 at the upper and lower ends of the operating shaft 5 should stand at the same angle to the axis of the operating shaft, and great

difficulty has heretofore been experienced in the practical operation of refrigerator car doors where the operating shaft has been made in the single piece, as any irregularity in the forging or other manufacturing operations is liable to cause the crank arms to stand at different angles so that only one of the crank arms will properly engage its keeper. To practically overcome this difficulty, I make the operating shaft in three parts, that is to say, of two shaft members 5, one at each end, and an intermediate connecting bar or member 4 which is preferably rectangular in cross section, although it may be made of any other suitable shape. Each 65 of the shaft members 5 is preferably a malleable iron casting and provided with a slot to receive the connecting bar of the shaft, which is rigidly attached by rivets 15, passing through the jaws or limbs 16 of the 70 shaft member 5. The shaft members 5 at each end of the operating shaft are preferably of the same form and construction, and each has a round portion 17 to fit in the bearing 18 which is secured to one of the 75 doors 2 of the car.

By making the operating shaft in three parts the cost of manufacture is materially reduced since the shaft bars 5, which are duplicates, may be made in a machine of 80 much smaller size than that required to make an operating shaft made in a single piece. This furthermore reduces the floor space occupied by these machines. And by making the shaft in three parts the same is 85 always insured of having the crank arms extending parallel to each other and in alinement.

I claim:

1. An operating shaft for refrigerator car doors and the like, said shaft comprising two, separate, relatively short end-members and an intermediate connecting bar to the ends of which said end-members are rigidly attached, each of said end-members having 95 a crank arm at its outer end.

2. An operating shaft for refrigerator car doors and the like, said shaft comprising two, separate, like, relatively short end-members, and an intermediate connecting bar 100

rectangular in cross section to the ends of which said end-members are rigidly attached, each of said end-members having a crank arm at its outer end and forked at its inner end where joined to the end of said connecting bar, each end member being also provided with a rounded bearing portion 17

intermediate its crank arm and its forked end.

JOHN F. O'CONNOR.
